[57] CLAIM

The ornamental design for a boat hull, as shown and described.

DESCRIPTION

FIG. 1 is a top plan view of a boat hull showing our new design;

FIG. 2 is a front elevational view thereof;

FIG. 3 is a rear elevational view thereof;

FIG. 4 is a bottom plan view thereof;

FIG. 5 is a side elevational view thereof, the opposite side elevational view being a mirror image of that shown;

FIG. 6 is a bottom perspective view thereof; and,

FIG. 7 is an enlarged fragmentary rear perspective view thereof.

FIG. 1

FIG. 2

FIG. 3

FIG. 5

FIG. 4

FIG. 7

FIG. 6
